Primary Examiner — Ian Simmons*Assistant Examiner* — Carissa C Fitts(74) *Attorney, Agent, or Firm* — Notaro, Michalos & Zaccaria P.C.(57) **CLAIM**

The ornamental design for a flexible flashlight, as shown and described.

DESCRIPTION

FIG. 1 is a top perspective view of a flexible flashlight showing my design therefor;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof;

FIG. 7 is a bottom plan view thereof;

FIG. 8 is view of the design of FIG. 1 shown in a different configuration; and,

FIG. 9 is a view of the design of FIG. 1 shown in a still further configuration.

The broken lines showing of the human figure in FIG. 9 is for environmental purposes. All other broken lines show portions of the article not claimed and form no part of the claimed design.

1 Claim, 9 Drawing Sheets---
